UNITED STATES PATENT OFFICE.

JOHN S. HOBSON, OF CHICAGO, ILLINOIS, AND JOHN S. HUNTOON, OF DETROIT, MICHIGAN, ASSIGNORS TO MASSEY CONCRETE PRODUCTS CORPORATION, OF CHICAGO, ILLINOIS, A CORPORATION OF VIRGINIA.

CRIBBING.

Original application filed June 10, 1926, Serial No. 114,899. Divided and this application filed July 7, 1927. Serial No. 203,920.

The present invention relates to cribbing, such as is used in the construction of retaining walls, railway embankments, piers, etc., and has particular reference to that type of 5 cribbing built up of successive courses of longitudinal stretcher units and tiers of transverse header units.

The present application is a division of our 10 application Serial No. 114,899, filed June 10, 1926, for cribbing.

The fundamental object of the invention is to provide an improved method of and 15 means for interlocking the stretcher and header units together. According to the present invention, this interlocking arrangement is obtained by forming the stretcher and 20 header units with matching depressions at points where they engage, and placing small bars or spheres in these matching depressions, which prevent relative shifting movement 25 between the stretcher and header units. By virtue of this construction a standardized type of unit may be employed for both headers and stretchers, although numerous advantages of our invention may be realized when embodied in stretcher and header units of 30 different types.

Referring to the accompanying drawings illustrating preferred adaptations of my invention:

Figure 1 is a front elevational view of the completed cribbing wall.

Figure 2 is a vertical sectional view through the wall.

Figure 3 is a fragmentary perspective view 35 illustrating the manner of erection.

Figure 4 is an enlarged detail view illustrating the interlocking depressions in the ends of the unit.

In the embodiment shown in Figures 1 to 4 inclusive, only one type of standard unit is employed, this unit serving alternately as a header and as a stretcher. This unit, designated 16, is constructed in the form of a 45 long bar of square or oblong section. It is preferably constructed of concrete, and when so made is re-enforced by any suitable wire or rod re-enforcing 17.

At each end of the unit transverse grooves 50 18 are molded in the unit, extending from side to side thereof and longitudinal grooves 19 are also molded in the ends of the unit

to intersect the transverse grooves 18. These pairs of grooves 18-19 are molded in two opposite sides of the unit, corresponding to 55 the upper and lower sides thereof. Both grooves are preferably of semi-circular form, although they might be of channel or other outline, the intersection of the two grooves 18-19 forming a T-shaped depression in 60 these upper and lower sides of the unit at both ends thereof. The transverse grooves 18 are spaced from the end of the unit a distance substantially equal to one-half the width of the unit. The longitudinal groove 65 19 is located centrally of the width of the unit, and preferably, although not necessarily, intersects the transverse groove 18.

Referring to Figure 3, it will be evident that when two of these units are laid end to end, with these grooved surfaces forming the top and bottom sides of the units, the longitudinal grooves 19 will align and form a co-extensive groove extending across both end portions of the units. When a third unit is now laid crosswise of these two longitudinal units, with its end extending squarely across the adjoining ends of the first two units, the transverse groove 18 of this third unit will register with the aligned grooves 70 19 of the first two units, producing a complete circular opening or groove defined in the contacting surfaces of these three units (Figure 3). A pin or bar 21 engaging in this circular opening will have its lower portion within the confines of the aligned longitudinal grooves 19 and its upper portion within the confines of the transverse groove 80 18 of the upper unit. Thus, this pin or bar 85 will interlock the three units together, effectively holding the two aligned units against pressures tending to force either or both of these units outwardly from under the end of the transverse unit.

This briefly describes the interlocking relation established between the stretchers and the headers and the manner of erecting cribbing walls with this type of unit. In constructing a wall such as shown in Figures 1 and 2, two parallel rows of units 16 are first 90 laid on the ground end to end and with the grooved sides constituting the top and bottom surfaces of these units. The ends are placed substantially in contact and the joints 100

of one row are placed exactly opposite the joints in the other row. These units thus occupy the relation of stretcher units and accordingly have been designated 16^a in Figures 1 and 2. Across these two rows of stretcher units, at each pair of joints, is then placed another unit, which unit occupies the relation of a header unit and accordingly has been designated 16^b. These header units are placed with their grooved sides constituting the upper and lower surfaces thereof. Just before these header units are placed on the joints of the stretcher units, the short pins or bars 21 are dropped in the aligned grooves 19—19 of the adjoining stretcher units. These pins or bars are of a diameter substantially to fill the completed openings. Thus, when the header units 16^b are placed over these joints, the transverse grooves 18 will engage over the protruding upper portions of the interlocking pins or bars 21, which pins or bars substantially fill the completed opening. Another series of these interlocking pins or bars are then placed in the transverse grooves 18 in the top sides of these header units 16^b and two second rows of stretcher units are then placed across the tops of these header units. The aligning longitudinal groove 19 of these stretcher units will drop over the pins which have been placed in the top grooves 18 of the header units, and thus the joint between these stretcher units and the top sides of the header units will also be interlocked by these pins. Thereafter another set of header units is then placed across this upper layer of stretcher units with the interlocking pins interposed as before described, and this process is repeated until the wall has reached the desired height.

It will be observed that the interlocking relation thus established between the stretcher units and the header units is of maximum effectiveness for preventing lateral or outward movement of the stretcher units relative to the ends of the header units or relative to each other. This re-enforcement against outward displacement is very desirable as the pressure of the fill 23 (of gravel, dirt, cinders or the like) has a tendency to force these stretcher units outwardly from the wall. There is practically no tendency for longitudinal displacement of the stretcher units as the end to end contact between these units takes care of these stresses.

The interlocking pins 21 preferably consist of short sections of round iron bar, although if the grooves 18—18 are of rectangular section pins of corresponding section may be employed therein. These pins or bars may be galvanized or otherwise rendered rust-proof if desired. The relatively small areas of the grooves 18—19 do not diminish the bearing area between the stretcher and header units materially, and the iron pins and the relatively wide expanse of concrete between

the grooves and the adjacent edges of the units oppose maximum sheering resistance against displacement of the units.

It will thus be observed that we have invented a novel and simple type of cribbing unit and cribbing structure in which the ends of the stretchers are formed with matching depressions, adapted to align the stretchers, and in which the headers are provided with matching depressions adapted to be placed over the depressions upon the stretchers forming a recess in which a simple inter-locking member may be placed. The engagement of the shoulders formed by the opposite sides of these depressions with the inter-locking members enables the headers to maintain the stretchers against outward movement, and when the cribbing has been built as described the weight of the structure is sufficient to maintain the units and inter-locking members in proper relation without additional fastening means.

While we have illustrated and described a specific embodiment of our invention, many modifications may be made without departing from the spirit of the invention and we do not wish to be limited to the precise details of construction set forth, but desire to avail ourselves of all changes within the scope of the appended claims.

Having thus described our invention, what we claim as new and desire to secure by Letters Patent of the United States is:

1. In a cribbing wall constructed of one type of standard unit serving both as a header unit and as a stretcher unit, said unit having T-shaped grooves in opposite sides at both ends thereof, said units being laid in superposed rows in relation to the stretcher units with tiers of such units interposed in the relation of header units, a portion of the T-shaped groove in each of said header units matching with a portion of the T-shaped grooves in adjoining stretcher units, and interlocking pins engaging in the matching portions of said grooves.

2. A cribbing wall constructed entirely of one type of standard unit serving both as a header unit and as a stretcher unit, said unit having formed at each end thereof a transversely extending groove set back from the end of the unit, and longitudinally extending grooves extending from the end of the unit and intersecting said transversely extending groove, said units being laid in courses in the relation of stretcher units and in tiers extending transversely of these courses in the relation of header units, the longitudinally extending grooves of adjacent stretcher units coinciding to form a co-extensive groove extending across the joint of adjacent stretcher units, the transversely extending groove of the adjacent header unit matching with the longitudinally extending grooves of the stretcher units, and interlocking pins in the

matching grooves of said header and stretcher units.

3. A cribbing wall unit comprising an elongated concrete member of substantially rectangular cross-section, having transverse semicircular grooves on opposite sides adjacent each end, and having longitudinal semicircular grooves on opposite sides extending inward from each end.
- 10 4. In a cribbing, the combination of a pair of stretchers laid end to end, each stretcher having a groove in its end communicating with a groove in the other stretcher, an interlocking pin in said grooves to align said stretchers, said pin projecting above said stretchers, and a header laid transversely on said stretchers and having a transverse groove to receive said pin whereby said header maintains said stretchers against lateral movement.

- 20 5. A cribbing wall constructed of stretcher units and header units, the bearing surfaces at each end of said stretcher units and at each end of said header units having matching depressions therein, and interlocking pins of substantially cylindrical form in said matching depressions and interlocking said units together.

6. A cribbing wall constructed of a plurality of standard units each having grooves formed in the opposite sides thereof at both ends of the unit, said units being arranged in courses of stretchers and transversely extending tiers of headers, the grooves in said header units matching with the grooves in said stretcher units when thus erected, and interlocking pins disposed in the matching grooves of said stretcher and header units for maintaining said stretchers in alignment and holding said stretchers from spreading by interlocking with said headers.

30 7. A cribbing wall unit comprising an elongated concrete member of substantially rectangular cross-section, said member having transverse semi-circular grooves formed on opposite sides adjacent each end for receiving a part of an interlocking pin of substantially cylindrical form having its other parts in a similar depression in a plurality of stretchers.

35 In witness whereof, we heretunto subscribe our names as follows:
